UNITED STATES PATENT OFFICE.

WILLIAM H. NIEMEYER, OF BALTIMORE COUNTY, MARYLAND.

STAMP-RACK.

1,361,538.

Specification of Letters Patent. Patented Dec. 7, 1920.

Application filed September 18, 1917. Serial No. 191,914.

To all whom it may concern:

Be it known that I, WILLIAM H. NIEMEYER, a citizen of the United States, residing in the county of Baltimore and State of Maryland, have invented certain new and useful Improvements in Stamp-Racks; and I do hereby declare the following to be a full, clear, and exact description of the invention, such as will enable others skilled in the art to which it appertains to make and use the same.

My invention relates to stamp racks.

The object of my invention is to provide a rack capable of supporting a plurality of stamps and combined with a mechanism for moving said stamps and stopping them at pre-determined locations so that any one of said plurality of stamps can be readily selected for use.

20 In the drawings:—

Figure 1 represents a front view of a stamp rack equipped with my improved operating mechanism.

Fig. 2 is a view of some of the parts shown in Fig. 1 looking in the direction of the arrow 2.

Fig. 3 is an enlarged view of the parts shown in Fig. 2 looking in the direction of the arrow 3.

30 Fig. 4 is a view of some of the parts shown in Fig. 3 looking in the direction of the arrow 4.

Fig. 5 is a view of some of the parts shown in Fig. 2 looking in the direction of the arrow 5.

15 represents a casing which is formed of a bottom 16, a right side 17 and a side corresponding thereto, (not shown) at the left of the stamp rack, a front 18, a top 19 and 40 a suitable back, not shown; these parts may be formed of wood, metal or any suitable composition, and joined together in any approved way.

Near the center of the side 17, a bearing 45 boss 20 projects through a hole provided in said side, the inner face of said boss being flush with the inside of the side 17. A shaft 21 is revolvably mounted in a hole provided within the boss 20 and the inner end of said 50 shaft fits tightly within a metallic flange 22 and is secured thereto by means of the pin 23. The metallic flange 22 is secured in any approved manner to the flange 24, which is preferably formed of wood.

55 On the left side of the stamp rack, a side similar to 17 is employed and this supports

a boss similar to the boss 20. A shaft similar to 21 is supported in the boss on the left side of the stamp rack and to this boss is secured a flange similar to the metallic 60 flange 22. A wood flange similar to the flange 24 is secured to said metallic flange at the left of the stamp rack and a plurality of shelves such as 25 is secured between the flange 24 and the wood flange at the left 65 of the stamp rack. Hence, it is evident that the flange 24, its similar at the left of the stamp rack and the shelves 25 form a unitary structure which is revolvably supported by the shaft 21 and its similar at the left of 70 the stamp rack, said shafts revolving freely in the boss 20 and its similar at the left of the stamp rack.

Each of the shelves 25 supports a plurality of stamps such as 26, these stamps being supported and guided in any approved manner but preferably as shown in my application for U. S. Letters Patent for stamp racks Serial No. 191913—Case D—filed on even date herewith. The means for supporting the stamps being described and claimed in said application will not be hereinafter referred to.

To the outer end of the shaft 21 a bevel gear 27 is secured by means of the pin 28 and a second bevel gear 29 fits tightly upon the shaft 30 and is secured thereto by means of the pin 31. The shaft 30 revolves freely within the bearing 32, said bearing and the boss 20 being formed integrally with the 80 bracket 33 and with the flange 34, the latter being secured to the side 17 by means of screws such as 35.

A forwardly extending index arm 36 is 95 formed integrally with the bearing 32 and the forward end of said arm is provided with a slot 37 in which is revolvably mounted the forward end of the index lever 38, said end being provided with a hole through which freely passes the pin 39, said pin being riveted in holes provided in the ears 40—40. The rear end of the lever 38 is provided with a hole in which is revolvably mounted the pin 41. The pin 41 is riveted in holes provided in the ears 42—42 of the index 100 sleeve 43.

The ears 42—42 are formed integrally with the large cylindrical portion 44 and the small cylindrical portion 45 of the index sleeve 43. The cylindrical portions 44 and 110 45 of the index sleeve 43 slide freely, respectively, in the large cylindrical hole 46

and the small cylindrical hole 47 provided in the index guide 48. The index guide 48 is formed integrally with the flange 49 and the latter is secured to the side 17 by means 5 of screws such as 50.

A retracting spring 51 is mounted in the large cylindrical hole 46 of the index guide 48 and presses toward the right against the large cylindrical portion 44 of the index 10 sleeve 43. The index sleeve 43 is provided with a large cylindrical hole 52 and a small cylindrical hole 53, the right end of the large hole being closed by the plug 54, and the latter is secured in place by the pin 55. 15 The index pin is composed of a small cylindrical portion 56 and a head 57 which slide freely, respectively, in the small cylindrical hole 53 and the large cylindrical hole 52 of the index sleeve 43, and a relieving spring 20 58 is placed in the latter hole between the head 57 and the plug 54, the pressure of said spring acting to normally keep the point 59 of the index pin in the position shown in Fig. 1.

25 The inner boss 60 of the index guide 48 is provided with a slot 61 in which slides freely the screw 62, the latter being threaded into a hole in the small cylindrical portion 45 of the index sleeve 43, the ends of 30 said slot serving to limit the motion of the index sleeve 43 in both directions.

A plurality of index sockets such as 63 is provided, each socket being driven in a hole in the flange 24, there being one index 35 socket for each of the shelves 25 and each socket is so located that when its corresponding shelf 25 is in the position shown as occupied by the shelf "A" in Figs. 1 and 2, the hole 64 in said socket shall be 40 opposite the point 59 of the index pin. The hole 64 is somewhat larger in diameter than the small cylindrical portion 56 of the index pin and the head of said socket is provided with a chamfered portion 65 for 45 a purpose hereinafter explained.

Since the index guide 48 is fixed in position, it is evident that the index sockets 63 are located at equal radial distances from the center of the shaft 21.

50 A sleeve 66 is revolvably mounted upon the shaft 30 in front of the end of the bearing 32 and a rearwardly extending arm 67, provided with the cam 68, is formed integrally therewith,—the cam 68 being located and shaped to contact with the cam follower 69, which is formed integrally with the lever 38 for a purpose hereinafter explained.

60 The index wheel 70 is formed integrally with the sleeve 71 and the latter is provided with a hole which fits tightly upon the front end of the shaft 30 and said sleeve is secured to said shaft by means of the pin 72. The face of the index wheel 70 is provided with a plurality of index holes 73,

there being one index hole for each of the shelves 25. Said face is further provided with a plurality of literal indicia 74 located thereon in line radially with the holes 73, there being one of said literal indicia for 70 each of the shelves 25.

The literal indicia 74 corresponds to the literal indicia 75 placed at the ends of the horizontal lines upon the index 98 in Fig. 1. There is one horizontal line on said index 75 for each of the shelves 25 and said horizontal lines are divided into a plurality of vertical series equal in number to the number of stamps that are to be placed upon each of the shelves 25, and each vertical series is 80 designated by a numeral.

The stamp rack is provided with a cover 76, inking pad 77, cover for the inking pad 78, a table 79 and a bracket 80 for supporting said table, all of these parts 85 being similar to those shown, described and claimed in my application for U. S. Letters Patent, Serial No. 149126, filed Feb. 16, 1917.

90 A selecting arm 81 is formed integrally with the sleeve 66, said arm being U shaped in contour and extending around the rim of the index wheel 70. At the bend of the U, the arm 81 is provided with an index pointer 82, formed integrally with said arm and the forward limb of the U is provided with a boss 83 and a selecting pointer 84 formed integrally therewith. The boss 83 is threaded and a sleeve 85 is screwed thereupon, said sleeve being provided with an extension 100 86. The boss 83, sleeve 85 and extension 86 are provided, respectively, with holes 87 and 88 mutually in line and in said holes, there is slidably mounted the selecting pin 89, said pin being provided with an enlargement 90 between which and the inside of the top of the sleeve 85 there is placed a spring 91 which serves to normally keep the pin 89 in the position shown in Fig. 5. The pin 89 is provided with a handle 92. A 110 detent pin 93 is driven tightly into a hole provided in the pin 89 and said pin slides freely in the slot 94 provided in the extension 86.

An index bracket 95 is secured to the front 115 18 by screws 96 and said bracket is provided with an index point 97 which is located adjacent to the rim of the wheel 70.

The operation of my improved stamp rack is as follows:—

120 By an inspection of the index 98 the operator ascertains the horizontal line upon which the stamp that he desires to use is indexed, he then notes the literal indicia 75 at the end of said line and the numeral at the 125 top of the vertical series in which the stamp he desires to use is indexed.

The operator then applies his hand to the handle 92 and pulls the same toward him, thus removing the point of the selecting pin 130

89 from the index hole 73 in which it may be resting and gives the handle 92 a slight motion of revolution, thus bringing the detent pin 93 over the outer face of the extension 86 and preventing the point of the selecting pin from re-entering the index hole 73.

5 The operator then moves the selecting arm 81 in either a clock-wise or counter clock-wise direction until the selecting pointer 84 comes opposite the one of the literal indicia 10 74 that corresponds to the literal indicia 75 that is at the end of the horizontal line of the index 98 upon which the desired stamp is indexed.

15 The operator then turns the handle 92 until the detent pin 93 drops into the slot 94 and permits the point of the selecting pin 89 to enter the one of the index holes 73 that corresponds to the literal indicia 74 that is 20 opposite the selecting pointer 84.

It is evident that when the point of the selecting pin 89 enters the appropriate one of the indexing holes 73 the index wheel 70 and the selecting arm 81 will be locked 25 together.

The operator then turns the index wheel 70 in either a clock-wise or counter clock-wise direction until the index pointer 82 comes opposite the index point 97.

30 When this happens, the shelf desired will occupy the position shown as occupied by shelf A in Figs. 1 and 2.

The operator then has merely to note the numerals placed upon the shelves just below the stamps and select the stamp corresponding to the numeral that is the same as the numeral at the head of the vertical series in which the desired stamp is indexed upon the index 98.

40 It is to be noted that the cam 68 contacts with the cam follower 69 only when the pointer 82 is opposite the point 97 or near thereto; at other times, said cam and cam follower are out of contact as shown in Figs.

45 1 and 3, and the retracting spring 51 keeps the index sleeve 43 and lever 38 in the positions shown in Fig. 1 and shown by full lines in Fig. 3. When, however, the pointer 82 is approaching the point 97, the cam 68 contacts with the cam follower 69 and moves the lever 38 from the position shown by full lines in Fig. 3 to the position shown by dotted lines in said figure, thus moving the point 59 of the index pin to the position 50 shown dotted in Fig. 1, and causing it to 55 enter the hole 64 of the index socket 63 and lock the flange 24 in position.

It is to be noted that during the approach 60 of the socket 63 to the position in which it is opposite the point 59 of the index pin, said point bears against the chamfered portion 65 of said socket and causes said point to move toward the right against the resistance of the relieving spring 58 until said point is

opposite the hole 64, and then said spring 65 forces the point 59 within said hole.

I claim:

1. In a stamp rack, the combination with a casing of bearing bosses supported thereby, shafts revolvably mounted in said bosses, revolving shelves supported by said shafts, means for revolving said shelves, index sockets revolving with said shelves, a stopping pin and means for inserting said pin in said sockets and means for withdrawing it therefrom.

2. In a stamp rack, the combination with a casing, of bearing bosses supported thereby, shafts revolvably mounted in said bosses, revolving shelves supported by 80 said shafts, means for revolving said shelves, index sockets revolving with said shelves, there being one socket for each of said shelves and said sockets being at equal radial distances from the center of said shafts, a stopping pin and means for inserting said pin in said sockets and means for withdrawing it therefrom.

3. In a stamp rack, the combination with a casing, of bearing bosses supported thereby, 90 shafts revolvably mounted in said bosses, revolving shelves supported by said shafts, a gear on one of said shafts, a shaft extending toward the front of said casing, a gear secured to one end of said shaft and meshing with said first-named gear, a hand wheel secured to the other end of said shaft, a selecting arm revolvably mounted on said shaft, and a selecting pin carried by said arm and located to enter said index holes 100 95 and lock said hand wheel and arm so that they will revolve together.

4. In a stamp rack, the combination with a casing, of bearing bosses supported thereby, 105 a shaft revolvably mounted in said bosses, revolving shelves supported by said shafts, a gear on one of said shafts, a shaft extending toward the front of said casing, a gear secured to one end of said shaft and meshing with said first-named gear, a hand wheel secured to the other end of said shaft, a selecting arm revolvably mounted on said shaft, a selecting pin carried by said arm and located to enter said index holes and lock 110 115 said hand wheel and arm so that they will revolve together, an index bracket supported by said case and an index pointer on said arm.

5. In a stamp rack, the combination with a casing, of bearing bosses supported thereby, 120 a shaft revolvably mounted in said bosses, revolving shelves supported by said shafts, a gear on one of said shafts, a shaft extending toward the front of said casing, a gear secured to one end of said shaft and meshing with said first-named gear, a hand wheel secured to the other end of said shaft, a selecting arm revolvably mounted on said 125

shaft, a selecting pin carried by said arm and located to enter said index holes and lock said hand wheel and arm so that they will revolve together, an index bracket supported by said case and an index pointer 5 and a selecting pointer on said arm.

6. In a stamp rack, the combination with a casing, of bearing bosses supported thereby, shafts revolvably mounted in said bosses, revolving shelves supported by said shafts, means for revolving said shelves, index sockets revolving with said shelves, a stopping pin, a bearing mounted on said casing, an operating shaft revolvably mounted in said 10 bearing, gearing between said operating shaft and one of said first named shafts, a 15

selecting arm revolvably mounted upon said operating shaft, means for selectively connecting said arm and operating shaft, a cam upon said arm and a cam follower and connections for operating said pin. 20

7. In a stamp rack, the combination with revolving shelves and index sockets secured thereto, of an index pin located to enter said sockets, an index sleeve for supporting said pin, a spring in said sleeve pressing said pin toward said sockets, an index guide for supporting said sleeve and a spring in said guide pressing said sleeve away from said 25 sockets. 30

In testimony whereof, I affix my signature.
WILLIAM H. NIEMEYER.
